UNITED STATES PATENT OFFICE.

FRANK T. WIECHERT, OF LAKEWOOD, OHIO.

DESIGN FOR A SODA-FOUNTAIN.

58,652.

Specification for Design.

Patented Aug. 2, 1921.

Application filed September 22, 1920. Serial No. 412,102. Term of patent 3½ years.

To all whom it may concern:

Be it known that I, FRANK T. WIECHERT, a citizen of the United States, residing at Lakewood, in the county of Cuyahoga and State of Ohio, have invented a new, original, and ornamental Design for Soda-Fountains, of which the following is a specification, reference being had to the accompanying drawing, forming part thereof.

The figure is a perspective view of a soda-fountain, showing my new design.

I claim:

The ornamental design for a soda-fountain, as shown.

FRANK T. WIECHERT.
